BAT PACKAGE

Michael Luery, Wabash, Ind., assignor to American Rock Wool Corporation, Wabash, Ind., a corporation of Indiana

Application September 12, 1936, Serial No. 100,483

3 Claims. (Cl. 206—46)

My invention relates to packages or containers and has to do more particularly with a package especially adapted for use in connection with bulk bats of fibrous material, more particularly for bulk bats of rock wool and the like.

In the rock wool industry it has been customary to prepare bats of rock wool to facilitate handling the material, said bats being of predetermined thickness convenient for application into the walls of buildings, stoves, refrigerators, etc., for insulating purposes. In the manufacture of such bats it has been considered necessary to introduce a binder into the fibers coincident with the formation thereof and, after the material has been 10 felted and formed into a bat, the material has been compacted sufficiently to retain its shape so as to permit its handling by a workman. After cutting such material into bats of a convenient size, it is usually packed into cartons for shipment, with a separator of paper or the like between the bats, whereby a workman can withdraw the bats from the package by grasping the edges of the separator sheets.

Such material has certain disadvantages. For 25 example, the use of a binder involves an additional expense and also introduces certain engineering problems into the process of manufacture. Furthermore, the presence of a substantial amount of binder in the finished product reduces the efficiency of the material as a heat insulator and detracts from its fireproof qualities. However, in spite of such disadvantages, bats are 30 considered highly desirable because of their convenience of handling.

It has long been customary in the rock wool industry to produce a product known as "loose wool", which consists of fibers produced without a binder and customarily packed loosely in bags or the like. Such material has been used by 35 withdrawing handfuls from the bag and applying it where desired, as in a wall or the like. Although such material is superior to the bats so far as thermal efficiency is concerned and is considerably less expensive to produce, it obviously is inconvenient to handle since it will not hold its shape and tends to fall in a heap when placed in a vertical wall or the like.

It has heretofore been found impractical to pack such unsized mineral wool in packages such 50 as bags, etc. in the form of a "bulk bat", i. e., a loose stack of stratified interlaced fibers, because it is practically impossible to handle such material in this condition. When attempts are made to withdraw such material from the package by 55 grasping the edges of a plurality of strata, the

material breaks in the fingers and cannot be withdrawn in the form of a bat.

An object of my invention is to provide a bulk bat of mineral wool in combination with a package which is so designed that the package may 5 be partially removed from the material so as to expose a portion thereof, whereby the hands of a workman may be inserted under a predetermined thickness of material, and such material thus be easily removed as a bat and deposited as 10 such in a wall or other place where desired. I thus make available mineral wool in its preferred unsized condition and so disposed that a workman may obtain a bat of the same of any desired thickness. My invention thus provides all 15 of the advantages of the sized bat along with those of loose wool, with none of the disadvantages of either.

Another object of my invention is to provide 20 a package or carton which will serve as a shipping container for a bulk bat of rock wool and the like, and which will also serve as a support while said material is being used.

In accordance with my invention, I provide a 25 package or carton in which a bulk bat of rock wool may be packed and sealed for shipment, said carton being capable of being partially opened along weakened areas, exposing the contents, so that bats of any desired thickness may be removed.

My invention will be more fully understood by 30 reference to the drawing forming a part of this specification and illustrating a preferred embodiment of my invention, wherein

Fig. 1 is a perspective view of a closed carton 35 embodying my invention; and

Fig. 2 is a perspective view of a package of bats from which the carton has been partially stripped to permit unpacking said material.

The numeral 10 refers to a carton formed of 40 beaver board, chip board or other suitable inexpensive material, said package being preferably in the form of a rectangular parallelopiped and having side walls 12, each of said side walls having a hinged flap 13 at the top thereof, and 45 a similar flap (not shown) in the bottom thereof. Said flaps fold inwardly as shown in Fig. 1 to close the package for shipment and storage.

The corners 16 which connect the side walls 12 are weakened, so that, after the package has 50 been opened, said side walls may readily be stripped downwardly along said weakened areas 15, as in the manner of peeling a banana, rendering the contents 55 readily accessible.

The contents of the package comprise a "bulk

bat" 23 of mineral wool or the like. Said material, as described above, consists of mineral wool fibers which have been deposited on a traveling belt or other surface in loosely felted, stratified condition and then cut to a predetermined size so as to be readily disposable within the package.

It will be apparent that, in accordance with my invention, the contents will be readily accessible, 10 after the sides of the package have been partially stripped away, as shown in Fig. 2. The workman may remove a bat of predetermined thickness by merely inserting his hands under the desired thickness of the material and gently working 15 such material loose from the strata below his hands. He will then hold a bat which may conveniently be disposed in a vertical wall or in any other position and which will retain its shape without collapsing in the manner characteristic 20 of loose mineral wool.

It will thus be seen that, in accordance with my invention, I have provided, at a low cost, mineral wool or the like in its preferred condition, without binder, and in such form that it may be 25 quickly and expeditiously handled by a workman.

Various changes coming within the spirit of my invention may suggest themselves to those skilled in the art, and hence I do not wish to be limited to the specific forms shown or uses mentioned,

except to the extent indicated in the appended claims, which are to be interpreted as broadly as the state of the art will permit.

I claim:

1. In combination, a bulk bat of mineral wool having parallel planes of cleavage, and a container therefor comprising side walls secured together along weakened corners, whereby said walls may be stripped from the contents along said corners, and closure flaps at the top and bottom of said side walls, said cleavage planes being perpendicular to said corners. 5

2. In combination, a bulk bat of unsized mineral wool having parallel planes of cleavage, and a container therefor comprising side walls secured together along weakened corners, whereby 15 said walls may be stripped from the contents along said corners, and closure flaps at the top and bottom of said side walls, said cleavage planes being perpendicular to said corners. 10

3. In combination, a bulk bat of fibrous material having parallel planes of cleavage, and a container therefor comprising side walls secured together along weakened corners, whereby 20 said walls may be stripped from the contents along said corners, and closure means at the top and bottom of said side walls, said cleavage planes being perpendicular to said corners. 25

MICHAEL LUERY.
